(57) **CLAIM**

The ornamental design for an exhaust cleaner for air pressure device, as shown and described.

DESCRIPTION

FIG. 1 shows a front view of an exhaust cleaner for air pressure device showing my new design;

FIG. 2 shows a rear view thereof;

FIG. 3 shows a top view thereof;

FIG. 4 shows a bottom view thereof;

FIG. 5 shows a left side view thereof;

FIG. 6 shows a right side view thereof;

FIG. 7 shows a top, front and left side perspective view thereof;

FIG. 8 shows a top, rear and right side perspective view thereof; and,

FIG. 9 shows an enlarged cross-sectional view thereof, taken along line 9—9 in FIG. 1.
